RECD. 285.1

UNITED STATES PATENT OFFICE.

CHARLES E. HOPKINS, OF NEW YORK, N. Y.

MACHINE FOR CASTING AND FINISHING CURVED STEREOTYPES.

1,286,324.

Specification of Letters Patent.

Patented Dec. 3, 1918.

Original application filed March 13, 1907, Serial No. 362,111. Divided and this application filed September 22, 1917. Serial No. 192,771.

To all whom it may concern:

Be it known that I, CHARLES E. HOPKINS, a citizen of the United States, residing at New York, in the county of New York and 5 State of New York, have invented a new and useful Machine for Casting and Finishing Curved Stereotypes, of which the following is a specification.

This is a division of my Patent No. 10 1,240,850 granted September 25, 1917, on apparatus for finishing curved stereotypes originally filed Mar. 13, 1907.

The present invention consists of improvements in apparatus for transferring, 15 from the casting boxes into position to be finished, curved stereotypes such as are cast in that described in the specification of British Letters Patent 12850 of 1903 and 4300 of 1906 and U. S. Patent 733,202. The 20 apparatus described therein included hand means for transferring the newly cast and therefore unfinished stereotype from a stereotype-transferring frame D^2 to the top surface of a drum or stereotype receiver. 25 The specification of an intermediate Patent 19333 of 1905 described a finishing apparatus in which the newly cast stereotype was placed upon a receiver and moved by hand along the latter to a hollow cylinder. 30 The objects of the present invention are to improve some of my prior inventions in this line, in which certain relationships are shown between a stereotype receiver and the finishing mechanism, so as to provide a receiver independent of all cutting means and 35 so related to the casting box as to receive the stereotype therefrom and bring it into proper position at the end of the finishing mechanism to slide directly into the latter longitudinally; to provide an improved 40 receiver in the form of a skeleton frame for receiving the stereotype directly from the casting box, and to provide improved means for removing the plate from the mold in 45 which it is cast and leave it in position to be finished.

Referring to the accompanying drawings which are to be taken as part of this specification and read therewith,

50 Figure 1 is a front elevation showing the improved associated casting apparatus and receiver in the "at rest" position;

Fig. 2 is a side elevation corresponding with Fig. 1;

55 Fig. 3 is a plan corresponding with the

"at rest" position of Fig. 1, but omitting the stereotype;

Fig. 4 an enlarged front elevation showing three different positions of the stereotype carrying frame and its coöperation 60 with the stereotype receiver;

Fig. 5 a sectional front elevation showing the coöperation of the stereotype receiver with the starting lever of the finishing apparatus;

Fig. 6 is a left-hand side elevation of Fig. 5 looking at it in the direction of the arrow;

Fig. 7 is an enlarged section of part of the driving connections;

Fig. 8 is an enlarged side elevation, looking at Fig. 9 in the direction of the arrow, of the same connections;

Fig. 9 is an enlarged front elevation and section corresponding with Figs. 7 and 8;

Fig. 10 is an enlarged detail side elevation of the starting rod and connected parts, in the "at rest" position, and

Fig. 11 is a like elevation of the same parts when the stereotype is on the receiver, 80 the detent disengaged from the ratchet wheel and the driving clutch on the point of being closed.

In the apparatus of British Patent No. 12,850 of 1903, the stereotype was cast between a fixed upright cope C and a drag movable away from it. The drag carried a transferring frame D^2 semi-circular in front elevation and the newly cast stereotype lay upon it, printing face downward, as shown 85 in Fig. 4 hereof. It is pivoted by the pivot d' to the respective side of the bottom D' of the drag, as shown in Figs. 1, 3 and 4, so that swinging it upward and to one side, puts the said stereotype into a reversed position, i. e. with its concave face downward. The object of swinging the said stereotype into this position, was to make it meet the frame D^2 , by the upward motion of the latter, and coöperate with the cutters that cut 90 off the riser and valve slug and beveled the ends of the stereotype.

According to the present invention, the receiver is independent of all cutting means, is located at the end of the finishing mechanism, and is a semi-circular frame instead of a drum, such frame consisting of two parallel bars 21, 22, each having a horizontal ledge 23, 24 the latter being positioned to re- 100 105 110

ceive and support the said stereotype as shown best in Fig. 4, the segments being cut away along the line 35^a Fig. 4, to enable the transverse ribs 25, Fig. 4, and the sprue 35 that is cast in the valve nozzle 45 of the cope C, to clear them when the conveyer pulls the stereotype off the receiver. The ledge 24 has a central ridge 24^a—Fig. 4—extending for the full length of it to engage in a corresponding groove in the respective side edge of the said stereotype. It is similar to the angle bar 103 of the British Patent 4300 of 1906 and serves the same purpose. The segments 19, 20 stand well within the length of the printing face of the stereotype 100, as shown in Fig. 2, in order that the riser 26 and valve slug 27 as well as the lug 28 on the concave face of the riser 26, and which the conveyer seizes hold of when the latter has to pull the newly cast stereotype off the receiver 19—24, into the hollow finishing cylinder 213, may all three overhang the said segments. This receiver is pivoted by lugs 29, 30, which radiate from its segments 19, 20, at about its center, to the adjacent ends of levers 31, 32, fulcrumed on a fixed axis 33 in the frame 34 of the finishing apparatus. The opposite ends of the said levers carry rollers 36 and extend far enough toward the pivot line d' of the frame D^2 , for the said rollers to be engaged by projections 37 on the latter. Which projections will, when the frame D^2 is swung up, rock the said opposite ends downward, and the receiver 19—24 upward and toward the then approaching stereotype, as shown by the set of dot and dash lines A in Fig. 4. Further, this receiver is connected by links 38, 39, which are pivoted by their respective ends to pivots 40 located between its center and the side of it next to the frame D^2 , with a rod 41 on the frame 34, below the fulcrum line of the above mentioned levers 31, 32. The effect of such linkage is to rock the rising receiver far enough over to meet the rising stereotype, so that when they do meet, their circular contours shall be parallel with each other.

This improved receiver is so mounted and located in the apparatus with reference to the finishing cylinder 213, that when it has an unfinished stereotype upon it, its axis is a little lower than that of the finishing cylinder and a little to one side—the right—of it. The linkage just mentioned has the effect of making the improved receiver 19—24 hold the top of its ledges 23, 24 in the horizontal plane when the newly cast stereotype is ready for the conveyer to push it toward the finishing cylinder. 40^a is a so-called starting-lever fulcrumed upon the frame 34, having its longer arm under the edge 79 of the receiver and its shorter and opposite arm engaged with the top end of

a starting rod 41. The spring 44 is preferably a spiral one surrounding the rod 41 and resilient between the guide 42 and a collar 145 beneath it and fast on the rod 41. 46 is a collar fast on the same rod 41 above the guide 42 to prevent the return of the rod 41 rocking the nose of the lever 40^a too high for the side edge 79 to engage with it. The weight of the rod 41 supplemented (it may be) by a weak spring 44, is relied on to return it. 42, 43 are guides fast on the frame 34, for the rod 41 to slide in. The starting rod 41 has a bell crank lever 47 fulcrumed on it, (Fig. 6) this lever being generally parallel with the rod 41 and kept so by a spring 48 and a stop 49, the latter on the rod 41. The spring 48 is preferably a spiral one resilient between a lug 50 on the rod 41 and the top arm of the lever 47 and supported in its working position by a straight rod 51, fast by one end to the lug 50 and having the other passed through a hole in the said top arm of the lever 47, so that the latter can work freely over it. 52 is a lug on the lever 47 and 53 a projection on the side of a detent 54 pivoted on a fixed stud 54^a. 55 is a ratchet wheel combined with the driving clutch and 75 is a spring pulling from a fixed point in the frame 34 and on the detent 54 to engage it with the wheel 55. 95 The driving shaft 80 extends lengthwise of the frame 34 and is rotated constantly through a driving pulley 81. A worm 82 fast on it, drives a worm wheel 83 which is loose on a transverse shaft 84 in the rear end of the frame 34. The inner face of this worm wheel 83 is hollowed out to embrace several equally distanced driving pegs 84^a fast to it and projecting from it in lines parallel with its axis, as well as a driving clutch 85 fast on the transverse shaft 84. This driving clutch 85 has a radial driving pawl 86 pivoted on it, and a spring 87 fast to the clutch 85 and pulling the pawl 86 into the path of the pegs 84^a. Next to this driving clutch 85 is the ratchet wheel 55 above mentioned, loose on the transverse shaft 84, and having a radial driving arm 88 pivoted on its side and near its periphery, by a pivot 89 that is parallel with the shaft 84. A driving pin 89^a is passed through the nose of the driving arm 88, the ratchet wheel 55, the driving pawl 86 and the driving clutch 85, holding the four together. But the ratchet wheel 55 has an arcuate slot 90 about the pin 89^a to allow of it moving independently of the other three pieces 85, 86 and 88.

The finishing cylinder 213 is located on bearing rings 215 in front of the stereotype 125 receiver 19—24 (already described) and approximately axially aligned with the lower position of the latter. 218, 219 are two supports for the unfinished stereotype. They project radially inward from the internal 130

face of the cylinder 213, the former fixed and the latter movable nearly vertically, but both standing at the same level and in the same plane as the stereotype supports on the receiver, when the cylinder 213 is standing still and receiving the said stereotype. The internal diameter of this cylinder is equal to the external diameter of the unfinished stereotype, but the said level of the supports 218, 219 is lower than the horizontal diameter of the cylinder, so that there is a space 220 between the stereotype 100 and the arch of the cylinder 213 at the moment the conveyer leaves the unfinished stereotype on the supports 218, 219.

The stereotype 100 stands with one side edge of the fixed support 218 at a short distance from the adjacent cylinder face and with the opposite edge on the vertically movable support 219.

Operation.

The plate being cast the drag is moved out on its wheels d along a horizontal track d' and tipped to horizontal position with an unfinished stereotype lying on the frame D^2 ready for removal to the receiver 19—24 Figs. 1, 3 and 4. This removal is effected by rocking the frame D^2 on its pivot d' , whereby the concave face of the stereotype and the top of the receiver 19—24, meet, as shown by the dot and dash lines A of Fig. 4, the frame D^2 being thereupon swung down upon the bottom D' again (as indicated by dot and dash lines B of the same figure), so leaving the stereotype upon the receiver, as in the Patent 12850 of 1903. As the improved receiver 19—24 is rocked up by the engagement of the frame D^2 with it, the starting rod 41 drops, raises the left-hand end of the starting lever 40^a (Fig. 5, dot and dash lines), carries the stud 271 on the lever 47 down clear of the stud 270 on the radial arm 265, and the lug 52 (likewise on the said lever 47) below the level of the projection 53 on the detent 54. As soon as the stud 271 clears the stud 270, the spring 48 rocks the depending arm of the bell-crank lever 47 up to the stop 49, thereby placing the lug 52 vertically under and a little below the projection 53 Fig. 8. The receiver 19—24 with the unfinished stereotype on it, drops below its former position (the one shown by the dot and dash lines in Fig. 5) into the one shown by the full lines in Figs. 4 and 5. As it drops, its side 79 again engages the adjacent arm of the starting lever 40^a and raises the starting rod 41, thereby making the lug 52 engage the projection 53 on the detent 54 and disengage the latter from the wheel 55 (Fig. 11), whereupon the spring 87 pulls the ratchet wheel 55 through a short arc, thanks to the slot 90, and in the working direction, thereby rocking the driving pawl 86 about the driving pin 89 into the path of the

driving pegs 84^a, whereby the next following peg 84^a comes up to the driving pawl 86, closes the driving clutch and starts the shaft 84. During the last mentioned rise of the rod 41, the stud 271 found the stud 270 in its path and rocked it to the rear, thanks to the pivot 266 and spring 267.

The cam 262 begins to turn with the shaft 84 and worm wheel 92 to which the cam is fixedly connected. At that moment, the conveyer finger 247^a stands in its rearmost position, Fig. 2, full lines, the weight of the unfinished stereotype holding the finger 247^a down in the conveyer head 246^a and the bottom of the slot 249 holding the front portion 80 of the stereotype up, but at an angle too small to show in the figure. The cam groove 261 makes the conveyer move to the front, through the operation of rock shaft 256, arm 255, and links 257 and 254, far enough to deposit the unfinished stereotype upon the cylinder supports 218, 219. The stereotype having been thus deposited, the cam groove 261 stops the conveyer.

The act of clamping the untrimmed stereotype to the cylinder takes its weight off the conveyer finger 247^a and the latter is forthwith raised by its spring 248, the radial projection of the said finger from the center of the cylinder 213 being less than the radial distance between the concave face of the clamped stereotype and the said center. During the rotation of the cylinder 213, and while the stereotype, as it is being finished, is more or less below a horizontal diameter of the cylinder, the cam groove 261 moves the conveyer to the rear, stopping when the finger 247^a has passed beyond the rear end of the finished stereotype 100, Fig. 2, dot and dash lines b. During the time the conveyer is so stopped, the support 219 is lowered, and this lowering brings the top of the stereotype 100 low enough for the finger 247^a to engage its rear end. The cylinder 213 being now locked, the cam groove 261 moves the conveyer to the front again thereby causing the finger 247^a to eject the stereotype 100—Fig. 2, dot and dash and section lines c. As soon as the ejection is effected, the said groove returns the conveyer to the rear of the apparatus, the arm 264, 265 making the stud 270 engage the stud 271, thereby rocking the depending arm of the bell-crank lever 47 to the rear and moving the lug 52 from under the projection 53 on the detent 54, whereupon the latter is pulled by its spring 75 into engagement with the ratchet wheel 55 Fig. 10, thereby opening the driving clutch and bringing the apparatus to the "at rest" position with which this section of the specification began.

Although I have illustrated and described a preferred embodiment of the invention described herein, I am aware of the fact that many modifications can be made therein by 130

any person skilled in the art without departing from the scope of the invention as expressed in the claims. Therefore I do not wish to be limited to all the details of construction herein shown and described, but what I do claim is:—

- 10 1. In a stereotype machine, the combination of casting apparatus, finishing apparatus, a receiver adapted to receive a stereotype from the casting apparatus and to bring it into the proper position for being slid into the finishing apparatus, and means for sliding the stereotype from the receiver into the finishing apparatus.
- 15 2. In a stereotype machine, the combination of casting apparatus, finishing apparatus having a rotary cylinder, a receiver adapted to be brought into register with one end of the cylinder, and means to transfer a stereotype longitudinally from the receiver to the cylinder.
- 20 3. The combination with a horizontal finishing mechanism and an upright casting mold located beyond the end but at one side thereof, said mold having a drag movable down to horizontal position also at the end of the finishing mechanism but at one side thereof, and means for moving the cast plate from the drag to a position at the end of the finishing mechanism and in alinement therewith.
- 25 4. The combination with a horizontal finishing mechanism and an upright casting mold located beyond the end but at one side thereof, said mold having a drag movable down to horizontal position also at the end of the finishing mechanism but at one side thereof, means for moving the cast plate from the drag to a position at the end of the finishing mechanism and in alinement therewith, and means for automatically sliding the plate longitudinally into the finishing mechanism.
- 30 5. The combination with a horizontal finishing mechanism and an upright casting mold located beyond the end but at one side thereof, said mold having a drag movable down to horizontal position also at the end of the finishing mechanism but at one side thereof, means for moving the cast plate from the drag to a position at the end of the finishing mechanism and in alinement therewith, and means for automatically sliding the plate longitudinally into the finishing mechanism when the plate is moved into said alined position.
- 35 6. The combination with one member of a casting box adapted to cast a plate, of means for delivering the plate from said member with its printing face down, means for inverting the plate and moving it laterally, and a finishing mechanism in alinement with but beyond the end of the position of the plate when inverted.
- 40 7. In a curved stereotype plate making

machine, the combination of a casting mechanism, a finishing mechanism arranged out of alinement therewith, means for delivering a stereotype plate cast in the casting mechanism into alinement with the finishing mechanism, supports in the finishing mechanism for the plate, means over which the plate can be moved to said supports, and means for effecting a relative rocking movement between the supports and finishing mechanism to hold the plate.

8. In a curved stereotype plate making machine, the combination of a casting mechanism, a finishing mechanism, means for delivering a stereotype plate cast in the casting mechanism into alinement with the finishing mechanism, supports in the finishing mechanism for the plate, and means for effecting a relative rocking movement between the supports and finishing mechanism to hold the plate.

9. In a curved stereotype plate casting and finishing mechanism, the combination of a finishing mechanism, a back positioned at one side of the finishing mechanism, a frame pivotally movable as a whole from said back into a position at the side of the finishing mechanism, and means for delivering a stereotype plate from said frame into alinement with the finishing mechanism with the convex face of the plate up.

10. In a curved stereotype plate making machine, the combination of a frame, a casting mold supported at one side of the frame, a shaving knife extending lengthwise of the frame, a shaving arch above and alined with the shaving knife shaft, guideways alined with the shaving knife shaft, means for revolving the shaving mechanism, means for removing a curved plate from the casting mold to a position at the side thereof and alining it with the guideways so it can be moved into the arch, and means for causing the shaving mechanism to make one revolution and stop.

11. The combination with an upright back, of means for receiving a plate located substantially on a level with the top of said back in horizontal position, and means for moving the cast plates out of the back and for then elevating the plates into alinement with said receiving means.

12. The combination with an upright back, of means independent of all finishing mechanism for receiving a plate located substantially on a level with the top of said back, means for moving the cast plates out of the back, and into alinement with said receiving means, and an independent finishing mechanism in alinement with said receiving means.

13. In a machine for making stereotype printing plates, the combination with a mold for casting the plate, of a frame mounted adjacent thereto, means on said frame for

engaging the plate and separating it from said mold when the frame moves away from the mold, and guideways in position for receiving the plate from said separating means.

14. The combination with a vertical mold for casting a concave printing plate, of a swinging frame pivoted near said mold to swing on a transverse axis, means on the

swinging frame for engaging the plate on said mold and taking it away from said mold with the swinging frame, and guideways for receiving the plate from said frame longitudinally.

In testimony whereof I have hereunto affixed my signature.

CHARLES E. HOPKINS.
